UNITED STATES PATENT OFFICE.

WILLIAM C. WILLETS, OF LOS ANGELES, CALIFORNIA.

WATER COOLER.

Application filed June 30, 1927. Serial No. 202,545.

This invention relates to improvements in water coolers, and has for an object the provision of a device of this character which permits the cooler to operate at maximum efficiency.

At the present time so-called iceless water coolers include what is termed an olla for containing the water. This olla is formed of clay, and water on the inside thereof tends to moisten the clay, at least an osmosis action takes place, and this in conjunction with air permits a rapid evaporation, resulting in a cooling of the olla and hence a cooling of the water within the olla. However, the water may contain some minute organisms, and it is a known fact that air contains germs of all forms. It has been found that the average olla which contains water becomes sour within a short period of time, possibly 15 three weeks, if the water is not used up. Furthermore the periphery of the olla assumes a mouldy appearance, which is due in part to the presence of algae. In certain cases and in certain localities small worms 20 may grow, eventually reaching the interior of the olla, rendering the water unfit for use. When this occurs it is necessary that the olla be returned to the water company and the exterior surface of the olla is ground to remove the algae, mould, dust and the like 25 therefrom. After an olla has been ground several times it is rendered unfit for use as the wall thereof would be too thin. The chief difficulty seems to be that the olla surface is not sufficiently protected and while 30 a small amount of algae or mould or dust on the periphery thereof might not in any manner injure the water therein, yet the appearance of algae on the olla is not favorable to a user thereof. This is particularly true 35 when the olla are placed in factories.

With the idea of overcoming the faults above enumerated, my invention has for an object the provision of novel means which 40 may be utilized in conjunction with the olla to prevent, in a measure, the olla from becoming as quickly contaminated with algae, mould and the like, yet preserving a distinct air flow around the olla to the end that the 45 water therein is chilled.

Another object contemplates the provision of means whereby the container for the water maintains at all times a pleasing appearance.

Other objects will appear as the specification proceeds, and with such objects in view, the invention consists in the novel and useful

provision, formation, construction, association and relative arrangement of parts, members and features all as shown in certain embodiments in the accompanying drawing, described generally and more particularly pointed out in the claims.

In the drawing:

Fig. 1 is an elevation of an embodiment of the invention;

Fig. 2 is a vertical sectional view of one form of the invention;

Fig. 3 is a plan view, partly in section, of the embodiment of the invention shown in Fig. 2;

Fig. 4 is a partially vertical sectional view of a modified form of my invention; and,

Fig. 5 is a further fragmentary vertical sectional view of a modification of the invention.

Corresponding parts in the different figures are designated by the same reference characters.

Referring now with particularity to the drawing, I have designated the improved invention in the form shown in Figs. 1 to 3 inclusive by A, and in Figs. 4 and 5 by B and C respectively.

In the form A, a is the olla and b means adapted to surround the periphery of the olla and in part spaced therefrom. The olla a is indicated in Fig. 2 in dotted lines at 1, and, as will be seen, comprises a container provided with an enlarged neck portion 2. In addition the olla has a faucet 3 adjacent the base thereof. Ordinarily a rubber gasket is inserted within the mouth of the neck 2 of the olla and the neck portion of a demijohn 4 is placed within said neck of the olla and bears against the rubber gasket. This will, of course, maintain the demijohn in an inverted position as illustrated in Fig. 1, so that the contents or at least part of the contents of said demijohn will be received within the olla.

The olla may be supported from some suitable stand as shown at 5. However, this construction permits the olla to be in direct contact with any dust in the air. The means b, by surrounding the periphery of the olla, will prevent the dust from directly contacting with the olla and yet allow a circulation

of air between the said means b and the periphery of the olla. The means b includes an annulus having a side wall 6 provided with corrugated end portions 7 and 8. In addition the side wall 6 is provided with one or more perforations 9. These corrugations act as

a means for spacing the wall 6 from the periphery of the olla as shown at Fig. 2. The ends of said member *b* may be overlapped as shown at 10 and spotwelded, or otherwise secured. I likewise provide a cover 11, constituting a part of the means *b* and in the present instance the cover substantially conforms in outline to the curvature of the upper end of the olla. This cover is provided with a rim 12 and with a tapered wall 13. This tapered wall portion, as shown, is substantially a hollow cone in cross section, with that portion of said wall 13 surrounding the annular opening thereof beaded at 14. This wall 13 is provided with one or more perforations 15. When the parts are in assemblage with the olla received within the member *b*, it will be evident that air is allowed to circulate as between the member *b* and the periphery of the olla through the perforations.

The device designated by *B* includes a cover the same as before, which is identical with the cover of Fig. 2, for that reason like reference characters will be applied. However, 25 the body portion of the means surrounding the olla differs slightly from the form *b*. This body portion is designated as *c* and the periphery is substantially straight sided, as indicated at 16 with ends of said sidewall 30 formed with inwardly directed flanges 17 and 18. These flanges are annular in form and may be beaded as shown at 19 to lend rigidity and strength thereto. The side wall may be provided with one or more perforations 20 located above the flange 18 and the flange 17 may be provided with one or more perforations 25 21. The cover 11, which will fit upon this member *c*, is provided with perforations 15. Thus when the olla is confined within 35 the member *c*, with the cover in place, air may circulate through perforations 15, 20 and 21. Attention is directed to the fact that the member *c* is provided with a slot 22, so that the faucet 3 may be projected therethrough. 40 This construction is necessary because the spigot or faucet 3 is usually within the olla and it is intended that the members either *b* or *c*, should be placed thereover so as to surround the olla without the necessity of removing the said spigot or faucet.

The form of the device depicted at Fig. 5 includes a member *d* adapted to spacedly sur-

round the olla, and a cover 23. In this connection the member *d* is provided with top and bottom inwardly directed flanges 24, 55 which are conveniently formed by providing the member *d* with inwardly directed peripheral grooves. These said inwardly directed flanges formed by grooving the member *d*, act to space the greater area of said 60 member from the olla. Such flanges may be perforated if desired. The cover is substantially an annulus formed with a depending rim portion. It is intended that the form *C* should be provided with perforations lying 65 between the two inwardly directed flanges 24, so that circulation of air against the periphery of the olla may be effected.

Any one of the devices as shown in the drawing would be simple of construction and 70 is a protection for the olla as well as any water contained therein. The said members for protecting the olla may be formed of various materials, materials not being a feature 75 of the invention.

It is obvious that various changes, modifications and variations may be made in practising the invention in departure from the particular showing of the drawing without departing from the true spirit of the invention. 80

Having thus disclosed my invention, I claim and desire to secure Letters Patent:

1. In a device adapted to surround an olla to prevent direct air contact therewith, comprising an annulus, and means at ends of said annulus adapted to uniformly space said annulus from the periphery of said olla. 85
2. In a device adapted to surround an olla to prevent direct air contact therewith, comprising an annular metal member provided with inwardly directed fluted end portions adapted to space the said annulus substantially evenly from the body of the olla. 90
3. In a device adapted to surround an olla to prevent direct air contact therewith, comprising an annulus, and means at ends of said annulus adapted to uniformly space said annulus from the periphery of said olla, said annulus being formed with air circulation 95 openings. 100

In testimony whereof, I have signed my name to this specification.

WILLIAM C. WILLETS.
